UNITED STATES PATENT OFFICE.

JOHN FORSTER, OF ST. HELENS, ENGLAND.

APPARATUS FOR MAKING GLASS ARTICLES.

1,106,140.

Specification of Letters Patent.

Patented Aug. 4, 1914.

Application filed September 11, 1908. Serial No. 452,637.

To all whom it may concern:

Be it known that I, JOHN FORSTER, a subject of the King of England, residing at St. Helens, in the county of Lancaster, England, have invented certain new and useful Improvements in Apparatus for Making Glass Articles, of which the following is a specification.

This invention relates to apparatus for making glass articles and has particular reference to the making of glass cylinders from which window-glass is afterward made, although it is not restricted thereto.

The primary object of the invention is to dispense with human blowing and its attendant mouth and lung diseases which are frequently followed by early physical deterioration.

The chief feature of this invention is that in the mechanical blowing of glass the blow-pipe is swung and at the same time supplied with air under pressure.

Other features of this invention will be evident from the following description taken in connection with the accompanying drawings which illustrate, by way of example, apparatus for carrying this invention into effect, and in which:—

Figure 1 is a front elevation of the machine; Fig. 2 a plan of the same; Fig. 3 is a section on the line 3—3 of Fig. 2; Fig. 4 a section of the blow-pipe-carrier on the line 4—4 of Fig. 2; Fig. 5 is a section of the valve for controlling the air-supply; Fig. 6 a section of the connector for connecting the blow-pipe to the air-supply.

Like letters indicate like parts throughout the drawings.

Referring to Figs. 1 to 4, the apparatus used for forming the cylinder after a bulb has been made will first be described. Two girders A A have resting upon them a number of frames A¹ carrying two rails A² mounted at the same height. A rail A³ is mounted above, being supported by brackets A⁴ attached to the frames A¹. A carrier-frame B for the blow-pipe is made of steel tubing B¹. The carrier B is provided with axles B² and B³. Wheels B⁴ are mounted on the axle B² and on the axle B³. The wheels B⁴ run on the rails A² and the rail A³ engages the two wheels shown at the upper part of Fig. 2. The axle B² carries a vertical bracket C and this axle being rotatable the bracket C is also rotatable for a purpose

to be described. Two rods C¹ C¹ are bolted to the bracket C and to a bracket C¹⁴. Bolted to the rods C¹ is a member C² having a projecting piece C³ which normally rests on one of the rails A² as shown. The rods C¹ support pipes C⁴ and C⁵, these being connected together through pipes C⁶ and C⁷ between which is an air-controlling valve D and a stop-cock C⁸. The pipe C⁴ has connected to it a pipe C⁹ which is connected to a pipe C¹⁰, the union for the latter connection being supported on a bracket C¹¹ carried on one of the tubes B¹. The pipe C¹⁰ is connected by a pipe C¹² to a suitable source of compressed air. The pipes are connected, as just referred to, by means of unions allowing them to move in vertical planes relatively to each other. The pipe C⁵ has connected to it a pipe C¹³, the connection being such that with the parts in the position shown in Fig. 2 the pipe C¹³ can move about a vertical axis. The pipe C¹³ carries a connector E, hereinafter fully described, adapted to receive the end of the blow-pipe F. One end of the axle B² carries a plate G having attached to it a bracket G¹. On this bracket G¹ are mounted two rollers G² on which the blow-pipe can rest and be rotated. The plate G also supports a bracket G³ arranged to engage the upper side of the blow-pipe, this being best shown in Fig. 4. The part of the blow-pipe between two collars F¹ on it fits into a slot C¹⁵ in the bracket C¹⁴ where it is held by a member C¹⁶ adapted to slide against the action of a spring (not shown in the drawings) and having an operating handle C¹⁷. It will be evident that with the arrangement of parts as described above, the blow-pipe can be tipped about the axis of the axle B² and swung in the manner of a pendulum, while at the same time being rotated about its own axis and having air supplied to it through the pipes leading from the source to the connector E. The rails A² and A³ run right up to the heating or re-heating furnace H and at the side of the rails at which the blow-pipe is mounted a pit is provided. At the end of the rails away from the furnace, a cushion-stop or buffer A⁵ is arranged. This cushion-stop consists of a U-shaped member arranged to engage the axle B³ and mounted on a rod A⁶ sliding in a bracket A⁷. A spring A⁸ surrounds part of the rod A⁶ and has one end engaging

with the bracket A⁷ and the other end with the U-shaped member.

Referring to Fig. 5, the air-controlling valve D is shown in section. The valve proper D¹ is arranged in the tube or casing D², the latter having connecting pipes D³ and D⁴ for joining it to the pipes C⁶ and C⁷ respectively. The valve D¹ rests on a valve-seating D⁵ and is mounted on a stem or spindle D⁶ the outer end D⁷ of which is provided with a handle D⁸. The spindle D⁶ passes through a bushing D⁹ and between this bushing and the enlarged portion of the spindle D⁷ is arranged a spring D¹⁰. The valve D¹ is provided on its periphery with corrugations D¹¹ which allow air to pass it when the operator raises the valve off its seating by pressing on the handle D⁸ against the action of the spring D¹⁰.

Referring to Fig. 6 the connector E which receives the end of the blow-pipe F, comprises a cup-shaped member E¹ across the mouth of which is arranged a rubber ring E². The ring E² is held in position by a metal ring E³ attached by screws to the cup-shaped member E¹. The ring is of such internal diameter that the flanged end of the blow-pipe can be forced through to the position as shown in Fig. 6, when a joint is formed which is air-tight, but which permits of the blow-pipe being rotated about its own axis. The cup-shaped member E¹ has projecting from it a portion E⁴ in the form of a conical plug, and this fits into a casing E⁵ which screws on to the pipe C¹³. The plug E⁴ is held in position by a nut E⁶.

The apparatus is employed in the following manner for blowing glass cylinders, such as are required for forming window glass. The glass is gathered on the end of the blow pipe from the glass tank and is manipulated in any manner, and the blow pipe is then transferred to the machine to be blown. The machine being at rest with its front end swung over to the rear of the track for conveniently taking hold of the blow-pipe and glass bulb, the blow-pipe is fixed in position as described above. The operator can now swing or rotate or move forward or backward the blow-pipe and bulb and he at once proceeds to move the bulb forward until the glass enters the glass-tank or re-heating furnace H. When sufficiently heated it is withdrawn and swung like a pendulum and ro-

tated as desired, air being admitted while the cylinder is being drawn and blown.

This operation is repeated as often as necessary until the cylinder is drawn out parallel and of even thickness when the "bull" end of the cylinder has a piece of hot metal applied and a hole cut in the usual way. It is again re-heated and at the proper time withdrawn and swung into a vertical position. The rotary motion given by the operator causes the "bull" end to fall out parallel with the cylinder owing to centrifugal force, and in this way the cylinder is completed and taken from the machine by an ordinary carrier to the stands.

With the apparatus and in the manner described above, glass cylinders can be made without any human blowing. Further the output is greater than with human blowing in the ordinary way.

It is obvious that various modifications may be made in the method of carrying this invention into effect. The construction and method of operation described above is given merely by way of example, having been found particularly suitable in practice.

What I claim as my invention and desire to secure by Letters Patent is:—

In apparatus for manufacturing glass, a reciprocating carriage, a frame pivotally connected to said carriage comprising a plurality of brackets and a plurality of rods connecting said brackets to each other, a plurality of air pipes connected to said frame in parallelism with each other and arranged to move therewith, an air supply pipe connected to one of the last mentioned pipes, right-angle pipes connecting the pipes in parallelism with each other, there being a connection between the last mentioned pipes, a controlling valve in said connection, a blow pipe rotatably mounted in the frame, and a connector connected to one end of the blow pipe and one of the pipes in parallelism with each other, said pipe connections being arranged to supply air to the blow pipe; substantially as described.

In testimony whereof I have signed my name to this specification in the presence of two subscribing witnesses.

JOHN FORSTER.
